UNITED STATES PATENT OFFICE.

JAMES R. PAGIN, OF VALPARAISO, INDIANA.

DESIGN FOR A COMBINATION-LAMP.

42,771.

Specification for Design.

Patented July 9, 1912.

Application filed October 30, 1911. Serial No. 658,135. Term of patent 14 years.

To all whom it may concern:

Be it known that I, JAMES R. PAGIN, a citizen of the United States, residing at Valparaiso, in the county of Porter and the State of Indiana, have invented a new, original, and ornamental Design for Combination-Lamps, of which the following is a specification, reference being had to the accompanying drawing, forming part thereof.

Figure 1, is a front elevation of a combination lamp embodying my invention. Fig. 2, is a side elevation. Fig. 3, is a top plan, and Fig. 4, is a rear elevation.

The leading feature of my ornamental design consists in a lamp that is of greater dimension in one direction than the other, approximating the appearance of a compound circle, in which two half circles are separated and their ends are joined by relatively straight portions so as to make an elongated lamp.

In the figures of the drawing the design shown discloses how the feature of separated circles above referred to, lend themselves to an ornamental effect in which the contour of the various reflecting surfaces harmonize with the ornamental shape of the casing.

The general characteristics of the design comprise an elongated contour of the lamp casing 1, formed with substantially rounded ends 2, that are joined together by center portions. The side elevation discloses a forward projection or enlargement 3, that provides room internally for reflectors 4 and 5. The door 6, is hinged to this part of the lamp. It has the same external outline as the casing. Its open portion comprises end portions 7, that run into each other and its forward exterior edges are rounded. A slight bevel 8, is formed around the openings. This bears an ornamental relation to the conical reflector 4, that is placed within the upper compartment.

Ornamentally considered the end portions

7, of the door opening are separated by the forward edge 9, of a center partition 10, that carries the cone 4, and also supports a parabolic reflector 5, that projects into the lower compartment. The parabolic reflector 5, has a radially projecting flange 11, that passes behind the bevel 8, of the door and at its upper edge it is secured to the center partition 10. In front elevation, the ventilating hood 12, is of substantially the same contour as the casing body 1, though of a larger radius at its forward end. From this point it passes rearward gradually receding downward until it meets the body of the casing. It follows downward onto the sides of the casing and on each side ornamental ventilating openings 13, are formed of gradually reduced diameters, the largest being placed nearest the front of the lamp and the smallest, nearest its rear edge. The back 14, of the lamp is rounded slightly about the central axes and the outer edge 15, is also slightly rounded. The usual side bracket, lamp forks, door hinge and door fastener are employed.

By way of summary, the front aspect of the lamp comprises the ornamental features of an elongated outline, a small bevel on the inside edge of the door rim, a large conical continuation of this for the upper compartment, a broken extension ending in a parabolic or equivalent reflector in the lower compartment and a concentrically placed central reflector 15, at the rear of the upper compartment.

I claim—

The ornamental design for a combination lamp, as shown and described.

In testimony whereof I affix my signature in presence of two witnesses.

JAMES R. PAGIN.
